UNITED STATES PATENT OFFICE.

WOLFF KAUFMAN, OF PATERSON, NEW JERSEY.

RADIO RECEIVING CIRCUIT.

Application filed April 14, 1923. Serial No. 631,988.

This invention relates to radio receiving apparatus and more particularly to a novel circuit employed for the reception of radio communication, and has for its object the provision of a circuit which is simple in structure and schematic layout, efficient in operation and which in operation has decided advantages over other circuits for similar purposes.

10 A further object of the invention is to provide a circuit which with but few parts is simple in operation and highly efficient in selectivity.

15 Further objects of the invention will appear more fully herein.

The invention consists substantially in the construction, combination, location and relative arrangement of parts, all as will be more fully hereinafter set forth, as shown by the 20 accompanying drawings and finally pointed out in the appended claims.

Referring to the drawings:

Fig. 1 is a schematic view of a circuit embodying my invention.

25 Fig. 2 is a similar view of a slightly modified arrangement employing the circuit of my invention.

The same part is designated by the same reference character wherever it occurs 30 throughout the several views.

It is among the special purposes of my present invention to provide an electrical circuit and method of operation or a radio receiving system and apparatus for obtaining 35 maximum amplification of the received signal impulses by means of certain modification and alteration of the ordinary audion detector and amplifier circuits, and thereby obtain results with a single tube which would be impossible in accordance 40 with the systems now known without additional tubes or stages of amplification.

45 Referring to Fig. 1, which illustrates a simple schematic wiring arrangement embodying my invention, reference character 1 designates the antenna which is connected through the variable inductance tube to the earth 3. The secondary circuit of the receiving system includes the grid electrode 4 of the audion 5 which is connected through

the usual grid condenser 6 which is preferably shunted by the resistance element 7 and thence to the filament 8 of the audion 5, through the coil 9, which is inductively and variably coupled with the coil 2 in the primary circuit. The plate electrode 10 of audion 5 is connected to the grid electrode 4, preferably at a point between the grid condenser 6 and the secondary coil 9. This connection is made preferably through a condenser 12, and a high resistance path 13 is provided between the plate and grid electrodes. A variable tap connection 14 is provided for the inductance coil 11, which tap connection has two paths, one to ground 60 and the other through telephone receivers 15, space current source 16, to filament 8 of audion 5. If desired, and as shown, the telephone receivers 15 may be shunted by a condenser 17. The primary and secondary 70 circuits, in accordance with my invention are connected through a variable capacity 18, as shown. In Fig. 2 the schematic arrangement is slightly modified.

In this arrangement the tap connection 14 is, as before, provided with two paths, one of which leads to the aerial 1 and the other through the variable inductance 2 to the ground 3 and the telephone receivers 15, either with or without the shunting condenser thereabout, and connected between the primary circuit and the secondary circuit, i.e., between the filament electrode and ground. The filament electrode 8 is lighted in the usual well-known manner from a current source 20 through a variable resistance 21.

85 While I am not prepared at this time to give a full and complete scientific or analytical explanation of the operation of this circuit, I do not desire to be limited to or bound by any theoretical consideration thereof, the operation of which circuit obtains the following results:

In the first place, the circuit is extremely 95 efficient for the reception of telephone signals, and when being operated to receive telephone signals reception of spark signals is for all practical purposes eliminated, and thereby eliminates the disadvantageous ef- 100

fects of damp wave signaling on the reception of continuous wave signals. By controlling the variable elements—namely, the tap connection 14 of the inductance 11 of the 5 plate circuit—the tap connection on the primary inductance 2 and the condenser 18 bridged between the primary and secondary circuits, I have found that it is possible to obtain great selectivity and completely tune 10 out adjacent stations operating on a definite wave length and receive a distant station operating on the same wave length without interference. I have also found the system to be especially adapted for use in reception 15 of continuous wave signals and the audion 5 placed in a state of oscillation generation at a controllable frequency whereby if the beat notes method of reception is being employed the pitch or frequency of the beat 20 note may be readily controlled.

It will be observed that in each instance the circuit consists of a combined detector circuit and amplifier circuit; e. g., referring to Fig. 1, the detector circuit comprises the 25 grid electrode 4, the grid leak 13, condenser 12, the lower portion of the inductance 11, tap connection 14, ground 3, tuning condenser 18 and filament electrode 8, with the usual plate circuit 10, inductance 11, telephone receivers 15 and B current source 16. The amplifier circuit will be apparent as 30 follows:

The grid filament circuit consists of grid electrode 4, resistance 13, inductance 9, to 35 the filament electrode 8. The plate circuit in this instance comprises the plate electrode 10, a portion of the inductance 11, telephone receivers 15, and the B battery source 16 to the filament 8.

40 It may be that the foregoing constitutes one explanation for the efficiency of the circuit employed but, as above stated, I do not desire to be limited or restricted thereto as I desire to have the foregoing description 45 recorded in the illustrative sense rather than in the limiting sense.

In the practical operation of the system embodying my invention certain rules of 50 adjustment should preferably be observed to obtain the maximum results. Of course, these rules would differ somewhat in accordance with the type of signal (i. e., telephone or continuous wave) which is to be received and the degree of selectivity desired.

55 Where radio telephone reception is desired, it is necessary to keep the system from oscillating, whereas in continuous wave signal reception it is necessary to produce oscillation slightly above or below the frequency of the receiver signals, in order to obtain beats of an audible frequency in accordance with the Heterodyne method of reception.

60 It may be generally stated, however, that the frequency of the secondary circuit is

determined by adjustment of the condenser 18 and the degree of amplification controlled by adjustment of the tap connection 14, the latter adjustment also serving to control the oscillatory condition of the two.

70 While I have shown and described my invention as applied to a radio reception system, I wish it to be understood that I do not desire to be limited or restricted to the use thereof in connection with wireless 75 telephone or telegraph transmission or reception as distinguished from radio frequency signaling systems, for it will be readily apparent to those skilled in the art that features hereof may be employed in connection with wired wireless or carrier current signaling system or any other type of electrical signaling system at present employed in connection with vacuum tubes.

80 Many further modifications and changes 85 in details will readily be apparent to those skilled in the art without departing from the spirit and scope of my invention as defined in the claims, but having now set forth the objects and nature of my invention and having shown and described structures embodying the principles thereof, what I claim as new and useful and of my own invention, and desire to secure by Letters Patent is:

90 1. In a radio signaling system, the combination with an audion, having a grid-filament circuit, of a circuit including an inductance coil connecting the plate electrode of the audion with the grid electrode thereof, and a variable connection between said coil 100 and the filament electrode of the audion independently of said grid electrode connection.

95 2. In a radio signaling system, the combination with an audion, having grid-filament circuit and a direct current plate-filament circuit, of an inductance included in the plate-filament circuit, said direct current plate filament circuit having a tap connection from said inductance to ground, and a 110 telephone receiver and voltage source, connected between said tap connection and the filament electrode of said audion.

115 3. In a radio signaling system, the combination with an audion, having a grid-filament circuit, of a circuit including an inductance coil connecting the plate electrode of the audion with the grid electrode thereof, a variable connection between said coil and ground, and a telephone receiver and current source bridged between said connection and the filament electrode of said audion, said bridged connection having no portion thereof in common with the grid-plate circuit.

120 4. In a radio signaling system, an antenna-earth circuit having an inductance therein, and an audion and its circuits with the grid-filament circuit thereof conductively associated with said antenna-earth circuit and 130

the filament electrode of said audion, said connection including a telephone receiver.

5. In a radio signaling system, the combination with an audion having grid-filament and plate-filament and grid-plate circuits, of an antenna earth system including an inductance inductively coupled with the

grid-filament circuit, and a tuning condenser connected between said antenna earth circuit and said grid-filament circuit. ¹⁰

In testimony whereof I have hereunto set my hand on this 10th day of April A. D., 1923.

WOLFF KAUFMAN.
